SPARK PLUG AND METHOD OF MAKING
THE SAME

Adelbert J. Gogel, Maumee, Ohio

Application May 21, 1945, Serial No. 594,859

4 Claims. (Cl. 123—169)

1

This invention relates to spark plugs.

This invention has utility when incorporated in ignition devices, more particularly for holding or holding and sealing an insulator in the shell of a spark plug.

A major problem in spark plugs is to provide an efficient seal between the ceramic core and shell. The metallic shell and the insulator mounted therein have widely varying coefficients of expansion which must be compensated in order to prevent any leakage therebetween, even under extreme conditions such as are encountered in present day aeroplane uses. The temperatures and pressures to which a spark plug is subjected while in use vary widely and, in order that the plug may be maintained gas-tight, the different expansion rates of the materials used in the plug must be compensated for.

Means may be used to compensate for the widely variable coefficients of expansion of the different materials by employing a spring positioned between the insulator and the shell which offers a resilient means to compensate for these different expansions while the plug is in use and to maintain the required seal.

This invention contemplates the provision of a resilient member which is highly adaptable for this purpose, which is capable of being easily and economically manufactured and assembled in the production of the units and which serves in a combination highly efficacious for maintaining a satisfactory seal between the ceramic insulator and metallic shell of the spark plug or serving alone as the seal itself.

It is, therefore, a primary object of this invention to provide a resilient means positioned between the metallic shell and the insulator of a spark plug which is capable of compensating for variations of expansion of the different materials used in the fabrication of the device so as to maintain a seal between the parts under all operating temperatures to which the spark plug will be subjected during use in an internal combustion engine, even under the more extreme operating conditions, such as are frequently encountered in high altitude and heavy load aeroplane engines.

It is a further object of this invention to provide a resilient means for use between the insulator and shell of a spark plug to maintain a seal therebetween which is sufficiently flexible to prevent localization of breaking stresses upon the insulator and allow equalization thereof to obviate any injury such as a fracture of the insulator due to changes of temperatures or pressures to which

2

the plug may be subjected and to absorb and compensate for such regardless of the rapidity of variations of each or of any combination thereof.

Still another object of this invention is to produce a spark plug inherently embodying the desirable qualities of a seal and compensating means in various plug types and employing economical base materials easily acquired in abundant quantities and fabricated by ordinary skill.

10 Other objects and advantages of this invention relating to the arrangement, operation and function of the related elements of the structure, to various details of construction, to combinations of parts and to economies of manufacture, will 15 be apparent to those skilled in the art upon consideration of the following description and appended claims, reference being had to the accompanying drawings forming a part of this specification wherein like reference characters designate corresponding parts in the several views.

Referring to the drawings:

Fig. 1 is a longitudinal section of a spark plug embodying one form of the invention disclosed herein;

25 Fig. 2 is a view similar to Fig. 1 but showing the insulator core in elevation;

Fig. 3 is a longitudinal section, in part, of a modified construction of a plug embodying a form of the invention;

30 Fig. 4 is a plan view of a type of mesh material suitable to be employed in one way of forming a mat or bushing to be used between the spark plug core and shell;

Fig. 5 is a perspective view, partly broken away, 35 of a type of mat or self-sustaining resilient ring which may be formed from the material of Fig. 4;

Fig. 6 is a view similar to Fig. 4, showing a swatch of mesh material wherein its strands are on a bias or diagonally interwoven; and

40 Fig. 7 is a showing of a fragment of knit wire textile especially suitable in forming a self-sustaining resilient packing.

Referring to the drawings, particularly to Figs. 1 and 2, a metallic shell 10 is provided with an externally-threaded portion 12 extending from shoulder 14 of the shell. This externally-threaded portion is adapted to cooperate with an engine block (not shown), in which the plug is positioned during operation. The shell is provided with the usual polygonal portion 16 for convenient manipulation in positioning the spark plug in an engine block. Herein, extending from the lower end of and across the axis of the threaded portion 12 is ground electrode 18, spaced from a center electrode 20 to form spark gap 22. While

a more common type of gap is shown, the plug may embody any desirable form such as a cloverleaf, annular or other design.

The center electrode 20 is positioned in a ceramic insulator 24, and is of the alumina or other type, and extends therethrough in a central bore 26 having an intermediate seat 28, against which collar 30 of the electrode 20 may rest for longitudinal positioning of the electrode in the core. This electrode may be sealed in position in the center bore 26 in any convenient manner, as, for example, by a powder pack 32 or the like. The insulator core 24 is provided with an externally enlarged portion 36 providing shoulders 38 and 40. The lower shoulder 38 is adapted to rest upon an internal seat 42 within the shell 10 intermediate its length. In this type of construction, a gasket 44 is preferably positioned between the shoulder 38 and the seat 42 as a seal therebetween. This gasket may be of nickel, soft iron, an alloy, or other suitable material.

The upper end of the electrode may have electrical communication within the core with a contact terminal 46 which has threaded connection 49 with the core and extends outwardly therefrom and configured in any desirable form to receive a connection from an ignition circuit.

The shell 10 extends upwardly beyond the shoulder 40 to provide an annular chamber 48 about the core for receiving a flexible mat or bushing 50. This packing 50 is flexible in all directions, and is conveniently formed by compacting a mass, or from a convolved mesh strip 52. In the formation of the member 50, layers of a foraminous material may be rolled to form a ring or cylindrical body of dimensions to fill the chamber 48. A suitable material is a wire or other heat-resisting material, mesh or screen of a comparatively fine weave. When the multi-ply bushing is formed, it can be wound into a tight or highly compressed state with an exterior diameter slightly less than the chamber diameter, so that the bushing can be readily inserted thereto. Once inserted, there is a slight natural expansion of this highly resilient wad which securely locks it in the chamber. Following this assembly, ring 54 is placed against the exposed or upper edge of the mat and the upper perimeter 56 of the shell 10 is spun or peened thereover, thereby again compacting the mat and firmly holding its mass in position.

Even with this compacting, the bushing remains resilient, holding the seal gas-tight entirely about the shoulder 38 and compensating for any and all changes due to expansion between the body parts of the plug and defeating any localization of stresses. In the bushing formation, as by matting a mass of thread-like material, or by convolving a continuous strip of mesh, the resilient form may be of a pattern forming cylindrical insert 50 having rims 58, 60 to more or less interfit with the cross-sectional shapes of the chamber as defined by the shell and the insulator walls. This promotes a more complete packing in the finished plug. The base material 52 may be a mass of wires or a right-angle woven-wire mesh, providing square or rectangular interstices, or it may be a material 62 having a bias weave, either warp or woof, or both, diagonally crossing the strip extent. Or the bushing may be made of layers of mesh having different gauges and weaves, so that an insert may be formed, not only to fit in any type of plug, but to meet any and all working conditions for which the plug is designed.

The bushing may not only serve as a spring cooperating with the ring or gasket 44 to form a seal, it may provide the complete seal itself. Such a construction is found of value in many instances. For example, in a plug of the type wherein the insulator core is of practically constant diameter throughout, and its major portion 64 (Fig. 3) or the chamber 66 is of another form or capacity. This latter type plug is devoid of any shoulder seal and the core portion 64 may be of a constant diameter through the chamber 66 and so extend therebeyond. This core may be of any longitudinal exterior outline as desired but, for convenience, is herein shown as cylindrical with a packing 68 completely filling the chamber 66.

In the bushing construction, it may be desirable to provide a treated packing such as a filler for the interstices therein. When the matting is formed, or the screen material is wound, the resulting cylinder may be compacted or crushed together by external forces from all directions wherein all symmetry of the mesh is lost and a body is formed replete with minute labyrinths. These irregular chambers may be filled with an inert substance such as talc, a ceramic powder, or graphite, and such filler may or may not be treated as with an oil, a polymerized oil, or a drying oil, for example, tung, linseed, Perilla or China oil. The filler may furthermore be composed of any combination of these materials as the ultimate use to which the plug is designed may dictate or require for the most efficient operation. In the production of these bushings, the base mesh material may be wholly or in part coated with the inert material 70, either alone, or treated with an oil 72. The coating may be over the entire mesh, or either the inner or intermediate wraps, and the oil may be applied with the coating or subsequently applied by coating or immersion of the cylinders or the packed plugs therein.

It has also been found the packings may be, to meet certain conditions, loaded with plastics such as of the "Bakelite" type or with silicones, or these materials are used as binders for the fibers employed.

The bushings are formed by direct packing of a mass of the material or from layers or wraps of mesh material, wholly or partially loaded with the dry or treated filler and then compacted by squeezing into a highly resilient mass wherein the strands of the mesh are contorted into a non-uniform mass, thereby forcing the filler throughout to fill the multiple interstices. Such mass is packed directly into the chambers of the plug or is compacted to a size for ready insertion into the plug for assembly. The ring 54 may then be inserted and compression therefrom against the mass in the final assembly by peening or spinning the edge 56 reshapes the bushing into a chamber packing, tightly, yet resiliently gripping the insulator core and providing a satisfactory plug seal.

When the plug has been packed with a treated wad, it may then be allowed to dry at ordinary temperatures, or heated to a degree of heat which may even be of a magnitude and duration to produce a curing effect on some of the materials or that will polymerize any of the oils used.

The bushing, which either serves as a spring in connection with other sealing means, either alone or loaded, may be economically produced and assembled, and cooperates with other plug parts to form a superior product.

An especially desirable packing material is a wire textile 74 (Fig. 7) which may have a knit body either strip or tubular in form and is readily collapsed into a chamber or into a self-sustaining ring 50 for insertion into a chamber. The rings 50 may be reinforced by a suitable foraminous or other material 76.

The materials used for the packing may be combined with such heat-resisting threads or fibers 78 as asbestos, glass or the like.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope of the following claims beyond the requirements of the prior art.

What is claimed and it is desired to secure by United States Letters Patent:

1. In a spark plug, a metallic shell having an internal chamber provided with a seat therein, an insulator having a center electrode and an enlarged external portion disposed in the chamber cooperating with said seat and forming an annular chamber with the shell above the enlarged portion, a deformable gasket cooperating between the enlarged portion and said seat, a preformed resilient mat of metallic fibers conformed to fit the annular chamber between the insulator and the shell and positioned therein, and an inturned lip on the shell to cooperate with one end of the resilient mat to urge the mat and the enlarged portion of the insulator against said seat to coin the deformable gasket and to resiliently hold the enlarged portion thereagainst through the resiliency of the mat to form a seal with the seat.

2. In a spark plug, a metallic shell having an internal chamber provided with an inwardly extending seat, an insulator having a center electrode and an enlarged external portion defining a pair of shoulders, said enlarged portion disposed in said chamber with the lower shoulder cooperating with said seat and the upper shoulder providing an annular chamber formed between the insulator and the shell chamber, a deformable gasket positioned between the lower shoulder and the seat adapted to be coined therebetween, a preformed resilient mat of metallic fibers conformed to fit the annular chamber and adapted to be positioned therein to resiliently hold the lower shoulder against the gasket to form a seal, and means on the shell to cooperate with the resilient mat to form an anchor for the mat whereby the resiliency thereof acts against the upper shoulder of the insulator.

3. In a spark plug, a metallic shell having an internal chamber provided with a seat therein,

an insulator having a center electrode and an enlarged external portion disposed in the chamber cooperating with said seat and forming an annular chamber with the shell above the enlarged portion, a deformable gasket cooperating between the enlarged portion and said seat, a preformed resilient mat of metallic fibers conformed to fit the annular chamber between the insulator and the shell and positioned therein, an inturned lip on the shell to cooperate with one end of the resilient mat to urge the mat and the enlarged portion of the insulator against said seat to coin the deformable gasket and to resiliently hold the enlarged portion thereagainst through the resiliency of the mat to form a seal with the seat, and an inert filler for the resilient mat to fill the interstices thereof to aid in sealing.

4. In a spark plug, a metallic shell having an internal chamber provided with an inwardly extending seat, an insulator having a center electrode and an enlarged external portion defining a pair of shoulders, said enlarged portion disposed in said chamber with the lower shoulder cooperating with said seat and the upper shoulder providing an annular chamber formed between the insulator and the shell chamber, a deformable gasket positioned between the lower shoulder and the seat adapted to be coined therebetween, a preformed resilient mat of metallic fibers conformed to fit the annular chamber and adapted to be positioned therein to resiliently hold the lower shoulder against the gasket to form a seal, an inert filler for the resilient mat to fill the interstices thereof, and means on the shell to cooperate with the resilient mat to form an anchor for the mat whereby the resiliency thereof acts against the upper shoulder of the insulator.
